UNITED STATES PATENT OFFICE.

WILLIAM N. HOWDEN, OF SAN PEDRO, CALIFORNIA.

ARTICLE HOLDER.

Application filed October 20, 1926. Serial No. 142,898.

My invention is an article holder to suspend various articles from a wall or the like by a frictional engagement therewith.

An object of my invention is the construction of an article holder made of bent wire or rods, in which the pair of rods which grip the article will have the free ends supported by a relatively rigid cross structure, these gripping rods being movable towards and from each other and gripping through the spring action of the wire.

Another object of my invention is a holder in which the outer parts are slightly canted upwardly to allow ready insertion of an article and the gripping of an article between the holding ends slightly turns the opposite sides of the holder into a downwardly converging direction.

A feature of my invention is a holder to project horizontally from a wall or other supporting structure, the holder being preferably formed of a single wire having an eye to fasten to the structure. The double wires are built outwardly horizontally and then substantially horizontally parallel to the wall. Arms extend outwardly and then inwardly forming gripping arms, the free ends resting from the horizontal supporting base which is parallel to the wall.

My invention is illustrated in the accompanying drawings, in which:

Fig. 1 is a plan view of one type of article holder;

Fig. 2 is a front elevation of same taken in the direction of the arrow 2 of Fig. 1;

Fig. 3 is a side elevation taken in the direction of the arrow 3 of Fig. 1;

Fig. 4 is a plan view of an alternative construction;

Fig. 5 is a front elevation taken in the direction of the arrow 5 of Fig. 4;

Fig. 6 is a side elevation taken in the direction of the arrow 6 of Fig. 4.

In the construction of Figs. 1, 2, and 3, the article holder is made from a single strip of wire or rod having an eye 1 by which a screw or the like may secure the holder to a wall or the like. Vertical hanger strips 2 are formed by the double wire pressed close together and the horizontal supporting strips 3 are formed by bending the parallel wires outwardly horizontally from the wall. Base wires 4 then extend substantially horizontally and also parallel to the wall and are consequently at right angles to the hanger strips 2, this being formed by diverging the two parts

of the wire. Outwardly extending strands 5 are then formed, these strands converging together, the wire then being bent into inwardly converging strands 6. The gripping strands 7 form a return making a substantial rectangle of the parts 4, 5, 6 and 7, the free ends 8 extending across the top of the base wires 4.

Preferably the base wires 4 have the corners 9 slightly bent up above the horizontal. The strand 5 is preferably curved upwardly so that the outer corner 10 is at a slight elevation above the corner 9 and is therefore slightly above the support 3. The strands 6 are preferably slightly downwardly inclined so that the corners 11 are slightly depressed compared with the corners 10 and also depressed slightly below the base wires 4. The gripping strands 7 are slightly upwardly inclined from the corner 11, the free ends 8 as above mentioned riding on the base 4.

The manner of functioning of the holder of Figs. 1, 2 and 3 is substantially as follows:

An article such as a broom handle or other device to be suspended is pressed between the corners 11, being guided by the strand 6. In such operation the gripping strands 7 are pressed apart, the holder bending slightly at the corners 9. The device is then held by the gripping strands 7 engaging the handle of the broom or other article between same. The weight of the article thus pulls downwardly on the gripping strands 7 and gives a slight twist to the holder so that the strands 6 become slightly more inclined than when the device is in the normal position and also pull the strands 5 slightly together.

It is intended that articles to be gripped will distort the holder so that the gripping strands 7 will be substantially parallel when an article is held between same and as the holder is made of resilient material, there will be considerable inward pressure against the sides of the broom handle or the like holding same suspended.

In order to give greater rigidity to the device, a metal band 12 may be placed around the supporting strip 3, thus preventing the two wires forming this strip from spreading apart when an article is wedged between the corners 11 and the gripping strands 7.

The holder of Figs. 4, 5 and 6 is constructed in a somewhat similar manner with an eye

20 having hanger strips 21 formed by the two parallel wires and supporting strips 22 also formed of the two wires in parallel, the latter being bent outwardly at right angles to the strips 21 and at right angles to the wall or to the construction. Base arms 23 extend outwardly and at the same time diverge from the ends of the supporting strips. Strands 24 are extended outwardly from the wall but converge inwardly towards each, the strands 25 which function to guide the articles being gripped extending inwardly towards the wall and converging towards each other.

15 Bent sections 26 form part of the gripping strands, having a straight section 27 forming an extension inwardly from the bends, the free ends 28 of the wire riding on and being supported by the base arms 22. In this construction the base arms 23 are preferably slightly inclined upwardly so that the corners 29 are slightly above the supporting strips 22. The strands 24 are also slightly inclined upwardly so that the corners 30 are slightly above the corners 29 and above the supporting strip 22. The short strands 25 however tilt downwardly as well as converging so that the corners 31 are below the corners 30 and preferably below the corners 29 and if desired below the supporting strips 22. The gripping strands 26 and 27 are inclined upwardly so that as above mentioned the free ends 28 ride on the base arms 23.

35 It is to be understood that in both of the illustrations, the relative angular positions of the different strands and wires and the relative positions of the corners are somewhat exaggerated in the drawings to bring out the details of construction.

40 It will be seen referring to Figs. 4, 5 and 6 that the parts 23, 24, 25, 26 and 27 form a four sided figure in which the wires of the strands may readily give or bend at the corners 29, 30 and 31.

45 When an article is gripped in the holder of Figs. 4, 5 and 6 it is guided into position by the strands 25 pressing the corners 31 apart. This may cause a slight spreading of the supporting strip 22 or a bending at the corners 29. The article if round is preferably gripped between the curved sections 26. It is intended in this construction that when an article is gripped by the holder the gripping strands 27 will be substantially parallel and the strands 24 bent outwardly to a greater extent than shown. The weight of the article tends to pull the corners 31 downwardly, giving the strands 26 a slightly greater inclination than when the device is not supporting any article. If desired articles may be held between the gripping strands 27.

50 55 60 65 While the free ends of gripping strands are pressed slightly apart when an article

is gripped, it is to be understood that the metal is of sufficient rigidity that it will not bend too freely at the angular corners to allow such ends to spread too wide apart. Moreover, to prevent such ends from spreading there is a frictional engagement with the base arms and also a slightly forward slope of such base arms.

65 70 75 80 85 It will be noted that a characteristic feature of my article holder is that the free ends 8 and 28 of the gripping strands 7 and 27 ride on and are supported by the base wires 4 and 23, respectively having reference particularly to Figs. 1 and 4. Therefore, when a heavy article is engaged by the gripping wires, these wires are prevented from sagging downwardly at their inner free ends. Where in the specification and claims I refer to the free ends of the wire or of the gripping wires being supported or riding on base wires, this is intended as a relative characteristic.

90 95 100 While I have illustrated two forms of article holders having slight differences, it will be apparent that they have the same typical characteristics and that other holders could be designed in the same manner although the shape might be considerably changed.

105 110 115 120 125 Various changes may be made in the principles of my invention without departing from the spirit thereof as set forth in the description, drawings and claims.

What I claim is:

1. An article holder comprising a single wire having bent portions forming substantially two rectangles, the base sides of such rectangles being in substantial alinement, the adjacent sides of the rectangles forming gripping strands, the free ends of such strands such being the free ends of the wire riding on the base sides.

2. An article holder having a single strip of wire, said wire having two strands in parallel, means to attach same in a vertical position on a wall, the two contiguous strands in parallel extending outwardly from the wall at right angles, single strands forming base arms diverging substantially horizontally, the remaining parts of each end of the wire being bent into a closed figure or loop, the adjacent sides of such figures or loops forming gripping strands, the free ends of the gripping strands such being the free ends of the wire riding on the base arms.

3. An article holder comprising in combination a single strip of wire having a central bend forming an eye, a pair of parallel strands forming a vertical hanger strip, a pair of parallel horizontal strands at right angles to the hanger strip to extend horizontally from the wall, single diverging base arms, a four sided figure formed by part of the base arms, outwardly extending and

converging strands, inwardly converging strands and return gripping strands, said gripping strands being adjacent each other and having their free ends riding on the base

5 arms.

4. An article holder as claimed in claim 3, the corners of the outwardly extending and inwardly converging strands being at a higher elevation than the junction of the

10 converging strands and the gripping strands.

5. An article holder formed of resilient wire having base arms extending in opposite directions and substantially horizontally, means to attach same to a supporting structure, loops formed by the remaining parts of the wire, the adjacent parts forming gripping strands with their free ends such being the free ends of the wire riding on the base arms, the portions of the gripping strands

20 adjacent each other being of a lower elevation than the outer parts of the loop spaced furthest from the supporting structure.

6. An article holder comprising wires hav-

ing means to secure same to a wall, a supporting strip having contiguous parallel 25 wires extending horizontally outwardly from the wall, two base arms extending horizontally and parallel to the wall in opposite directions and at right angles to the supporting strip, loops formed from said base arms, 30 the adjacent parts of the loops forming gripping strands, the free ends of said strands such being the free ends of the wire riding on the base arms.

7. An article holder comprising a pair of 35 wires extending horizontally from a support, said wires being bent to diverge in a substantially horizontal plane and form base arms, outward and converging strands, inward and converging strands and gripping 40 strands, said gripping strands being adjacent and having their free ends riding on the base arms.

In testimony whereof I have signed my name to this specification.

W. N. HOWDEN.
